(57) **CLAIM**

The ornamental design for a chalk line marking apparatus, as shown and described.

DESCRIPTION

FIG. 1 is a front perspective view of the chalk line marking apparatus.

FIG. 2 is a back perspective view of the chalk line marking apparatus.

FIG. 3 is a left side view of the chalk line marking apparatus.

FIG. 4 is a right side view of the chalk line marking apparatus.

FIG. 5 is a back view of the chalk line marking apparatus.

FIG. 6 is a front view of the chalk line marking apparatus.

FIG. 7 is a top view of the chalk line marking apparatus; and, FIG. 8 is a bottom view of the chalk line marking apparatus.

The broken lines represent portions of the article that form no part of the claimed design.

1 Claim, 8 Drawing Sheets
